UNITED STATES PATENT OFFICE.

ALBERT BALL, OF CLAREMONT, NEW HAMPSHIRE, ASSIGNOR TO THE SULLIVAN MACHINE COMPANY, OF SAME PLACE.

SAND-BAND.

SPECIFICATION forming part of Letters Patent No. 447,288, dated March 3, 1891.

Application filed July 26, 1890. Serial No. 360,031. (No model.)

To all whom it may concern:

Be it known that I, ALBERT BALL, a resident of Claremont, in the county of Sullivan and State of New Hampshire, have invented 5 certain new and useful Improvements in Sand-Bands; and I do hereby declare the following to be a full, clear, and exact description of the invention, such as will enable others skilled the art to which it pertains to 10 make and use the same.

The object of the invention is to simplify and cheapen the construction of sand-bands and of the means of connecting them with an axle of a wheeled vehicle. Heretofore the 15 shells of sand-bands have been provided with an inner inturned flange, which was clamped between a screw-threaded nut placed within the shell adjacent to the flange and an exteriorly-screw-threaded holder fitted on the axle. 20 This holder has been made in the form of a mutilated or incomplete ring, being slotted for the reception of the axle. An extension or arm of said holder was embraced by the ordinary yoke, which holds together the wooden 25 and metallic sections of the usual form of carriage-axle and was thereby clamped to the bottom of the axle. By the present improvement the inner screw-threaded ring is dispensed with and an annular band or washer 30 is substituted, which band is clamped upon an inturned flange of the shell by means of a projection or projections from the head, which, being of malleable metal, are adapted to be swaged or forced down upon the band 35 and bind it to said head. In my application filed of even date herewith is shown a head secured directly to the shell by forcing the metal of the head upon the same. The present case relates to similar means of binding 40 an annular washer or ring upon an inturned flange of the shell by clinching or swaging portions of the head thereon in such manner as to grip the flange between the washer and the head. The holder above referred to is 45 provided exteriorly on its main part with screw-threads, which are continuous, with others formed on the axle upon which the exteriorly-screw-threaded head of the sand-band is screwed. 50 According to the present improvement the head of the sand-box is secured to this holder

by an externally-situated screw passing through the ring portion of the head and bearing upon the exterior of the holder, said ring portion being specially formed for the purpose. 55

The invention consists in the construction herein described and particularly pointed out.

In the drawings, Figure 1 is a central longitudinal section of a sand band or box. Fig. 60 2 is a similar view of the same secured upon an axle. Fig. 3 is a like view of a modified form. Fig. 4 is a plan of a clamping ring or washer. Fig. 5 is a central longitudinal section of said ring; and Fig. 6 is a plan of the 65 ring secured upon the head, the shell being omitted.

Reference-letter A indicates a sheet-metal shell of a sand band or box provided with an inturned flange C. 70

D denotes a head having a screw-threaded opening adapted to be screwed upon the axle, and K a clamping-ring. The flange C is secured between the rim of the head and said ring K by a projection L, formed integrally 75 with the head. These projections or rivets are passed through suitably-located holes in the flange and in the ring, and are then upset or clinched down upon the band, so as to bind the parts securely together. L is a common rivet for a like purpose. 80

H indicates a hole for the escape of sand.

F indicates the axle-holder secured to and embracing the axle in usual manner. The upper or wooden section of the axle and the 85 exterior of the bottom and sides of the holder have continuous screw-threads, which adapt them to engage the screw-threaded opening of the head.

G is a set-screw passing through an extension of the ring of the head in an inclined direction and engaging the holder in manner to lock them together. Heretofore a screw for a similar purpose has been placed within the sand-box. Such location is objectionable, as 90 it necessitates locating a hole in the sand-band adjacent to the screw, and also requires a considerable inward extension of the ring of the head and holder to furnish a seat for the screw. By the present arrangement the 95 screw is easily made accessible, and no special opening in the shell for its manipulation is 100

required. To provide for this I prolong the walls of the screw-threaded opening in the head toward the body of the axle sufficiently to provide room for a seat for the screw outside the shell, as shown, the projection of the wall-opening being indicated by D'.

I am aware that sand-bands have been provided with flanges that were held between disks and nuts, said nuts working on the axle-spindle and adapted to force the flanges against the disks, the latter being supported by shoulders on the axle, and such devices are not of my invention.

Having now described my invention, what I desire to secure by Letters Patent is—

1. In a sand band or box, a shell having an inturned flange, a band or washer, a head provided with a screw-threaded opening or

rim, and projections on the head engaging the band and forced down upon the same to grip the flange between the head and said band, substantially as set forth.

2. In a sand band or box, the shell having flange C, the head D, made of malleable metal, and the ring N, **said head being** provided with projections O, turned down and clinched upon the ring, substantially as set forth.

In testimony whereof I have signed this specification in the presence of two subscribing witnesses.

ALBERT BALL.
